United States Patent Office.

JOHN GOODIN, OF CENTRALIA, ILLINOIS.

Letters Patent No. 80,475, dated July 28, 1868.

IMPROVEMENT IN BORING AND DRILLING-MACHINES.

The Schedule referred to in these Letters Patent and making part of the same.

TO ALL WHOM IT MAY CONCERN:

Be it known that I, JOHN GOODIN, of Centralia, in the county of Marion, and in the State of Illinois, have invented certain new and useful Improvements in Combined Boring and Drilling-Machine; and do hereby declare that the following is a full, clear, and exact description thereof, reference being had to the accompanying drawings, and to the letters of reference marked thereon.

The nature of my invention consists in the use of a frame, provided with a long gear-wheel and a rack-bar, for giving the machine rotary as well as perpendicular motion, and which machine can be used for drilling as well as for boring.

In order to enable others skilled in the art to make and use my invention, I will now proceed to describe its construction and operation, referring to the annexed drawings, which form a part of this specification, and in which—

Figure 1 is a side view, and

Figure 2 is a front view.

A represents a platform or base, with an upright post or standard, B, on top of which the arm C is fastened and extends out beyond the post. The inner side of the post B is provided with a groove, a, in which the arm D runs. This arm is fastened to the upright rack-bar E, on top of which another arm, F, is secured, in such a manner as to form a frame, extending from the post B, in the same direction as the arm C on top of the said post.

The drill-shaft G runs through the arms C, E, and D, and is provided with a corrugated cylinder or roller, H, placed on the shaft, and extending the whole distance between the arms D and F, forming, as it were, a long gear-wheel for the drill-shaft. The lower end of said shaft, below the arm D, is provided with a socket, I, for the insertion of the auger or drill.

The shaft G is turned by means of a driving-wheel, K, provided with cogs on its inner periphery, and working into the corrugations on the cylinder or roller H, said wheel being placed in a frame, L, fastened to the side of the post B, obliquely, in such a manner that the cogs of the wheel work only at the lower edge thereof in the corrugations of the cylinder, when the wheel is turned by the crank M.

On the side of the post B are two ears, b b, which support the shaft c, which shaft is turned by the crank N, and is provided with a cog-wheel, O, which works in the rack-bar E, so that the drill-shaft G may by this means be raised or lowered, as may be desired.

Thus, after the boring is completed, the crank N and wheel O will raise the auger out of the wood, and the same arrangement is used as a lever-power in drilling by a reverse motion.

The machine is to be made of any suitable material, and of any size required, according to the kind of work designed to be performed.

Having thus fully described my invention, what I claim as new, and desire to secure by Letters Patent, is—

The arrangement of the corrugated cylinder H, inclined toothed wheel K, rack-bar E, cog-wheel O, and movable frame F, with the standard B, all constructed to operate as set forth.

In testimony that I claim the foregoing, I have hereunto set my hand, this 16th day of May, 1868.

JOHN GOODIN.
